HEAD SUPPORT FOR BEAUTY CHAIR

Gale Mullooney, 35 Park View Ave.,
Bronxville, N.Y. 10708

Filed Jan. 31, 1972, Ser. No. 222,440

Term of patent 14 years

Int. Cl. D6—06

U.S. Cl. D6—200

FIG. 1

FIG. 2

FIG. 3

FIG. 4

FIG. 1 is a front elevational view of a head support for beauty chair, showing my new design;

FIG. 2 is a side elevational view thereof, the opposite side being identical;

FIG. 3 is a top plan view thereof; and

FIG. 4 is a bottom plan view thereof.

I claim:

The ornamental design for a head support for beauty chair, as shown and described.
